No. 37,210.

Patented November 8, 1904.

UNITED STATES PATENT OFFICE.

SIDNEY M. COLGATE, OF ORANGE, NEW JERSEY.

DESIGN FOR A TOILET-POWDER RECEPTACLE.

SPECIFICATION forming part of Design No. 37,210, dated November 8, 1904.

Application filed September 10, 1904. Serial No. 224,041. Term of patent 14 years.

To all whom it may concern:

Be it known that I, SIDNEY M. COLGATE, a citizen of the United States, and a resident of Orange, in the county of Essex and State of New Jersey, have invented a new, original, and ornamental Design for a Toilet-Powder Receptacle, reference being had to the accompanying drawings, in which—

Figure 1 is a side elevation of a receptacle for containing toilet-powder and showing my design. Fig. 2 is an edge view of the same.

I claim as new and desire to secure by Letters Patent—

The ornamental design for a toilet-powder receptacle herein shown.

SIDNEY M. COLGATE.
